DESIGN FOR A PENCIL SHARPENER

Arthur M. Rapoport, New York, N. Y.

Application October 28, 1946, Serial No. 134,344

Term of patent 14 years

(Cl. D74—1)

To all whom it may concern:

Be it known that I, Arthur M. Rapoport, a citizen of the United States, residing at New York city, in the county of Kings and State of New York, have invented a new, original, and ornamental Design for a Pencil Sharpener, of which the following is a specification, reference being had to the accompanying drawing, forming a part thereof.

Fig. 1 is a front elevational view of a pencil sharpener, showing my new design.

Fig. 2 is a top view thereof.

Fig. 3 is an end view thereof.

Fig. 4 is a sectional view taken on line 4—4 of Fig. 1.

I claim:

The ornamental design for a pencil sharpener, substantially as shown.

ARTHUR M. RAPOPORT.
